UNITED STATES PATENT OFFICE.

JOHN J. GARD, OF HARVEY, ILLINOIS, ASSIGNOR TO BUDA FOUNDRY & MANUFACTURING COMPANY, OF CHICAGO, ILLINOIS, A CORPORATION OF ILLINOIS.

DEVICE FOR OPERATING SWITCHES.

No. 824,782.

Specification of Letters Patent.

Patented July 3, 1906.

Application filed December 7, 1904. Serial No. 235,871.

To all whom it may concern:

Be it known that I, JOHN J. GARD, a citizen of the United States, residing at Harvey, in the county of Cook and State of Illinois, have invented certain new and useful Improvements in Devices for Operating Switches, of which the following is a specification.

My invention relates to devices for operating railway signals, switches and the like, which devices are characterized by the use of mechanism which may be located either between or outside of the rails adjacent to the switch, and adapted to move the switch in either direction by means of apparatus actuated by fluid pressure, supplied and controlled from a distant point.

The objects of my invention are to provide an apparatus of an exceedingly simple and durable construction, in which the moving parts are thoroughly protected from the injurious effects of moisture, dirt, etc., or the passing of trains. To provide an apparatus in which the maximum amount of pressure will be utilized to operate the moving parts, and one in which the moving parts will be subjected to a minimum amount of wear upon their bearing surfaces.

These objects and other advantages which may hereinafter appear, I attain by means of the construction illustrated in preferred form in the accompanying drawings wherein—

Figure 1 is a top plan view of my improved apparatus, with the cover removed;

Figure 2 is a longitudinal section of the same, taken on the line (2) of Figure 1, and

Figure 3 is a cross sectional view, taken on the line (3) of Figure 1, illustrating the manner of connecting the operating lever to a switch point.

By reference to the accompanying drawings it will be seen that in my improved construction the moving parts thereof and those parts liable to be damaged by exposure, are inclosed in a casing 4 provided with a removable cover 5, secured thereto by means of screws, as shown, or in any other suitable manner. The joint between the cover and the casing being rendered water tight by an interposed gasket 6. The casing is also provided with outwardly projecting lugs 7, for securing it in position.

To the inside of one end of the casing is pivotally secured an operating lever 8; and a connecting rod 9, which passes through a stuffing box 10, tapped into one side of the casing, serves to connect the free end of the lever 8, to the switch point, as illustrated in Figure 3. Inflatable bags 11 are interposed between the lever 8 and the sides of the casing and serve to alternately shift the lever and in so doing impart motion to the switch point, through the medium of the rod 9, in a manner to be presently described.

In order to provide the maximum amount of bearing surface for the bags between the lever and sides of the casing, and to obtain the full benefit of such large surface during the entire period when the bags are being inflated, the opposite sides of the casing are made approximately parallel with the lever 8, when it is at the extreme limits of its stroke. The bags being thus approximately wedge shaped, it will be seen that the bearing surface is equally distributed throughout their entire length, thus adding greatly to the life of the bags and facilitating the movement of the lever. The bags are provided at their smaller ends with necks 12, secured to nozzles 13, projecting through the small end of the casing and adapted to be connected in any suitable manner to a supply of fluid under pressure.

In the operation of my device the bags are alternately inflated and deflated, such alternate action serving to shift the lever 8, in opposite directions. The inflation and deflation of the bags alternately may be controlled by any suitable arrangement of valves, located at a convenient point, but which does not form a part of the present invention.

From the foregoing it will be seen that my device may be located either between or outside of the rails at any desired point, as the rod 9, may project through either side of the casing without in any way changing the relative position of the parts. It will also be seen that the operative parts of my device are entirely inclosed in the casing and effectively protected from the injurious effects of dirt, moisture, etc., by reason of the gasket 6 and stuffing box 10.

Having thus described my invention and

illustrated its use, what I claim as new, and desire to secure by Letters Patent, is the following:

1. A switch operating device comprising a casing, a lever pivoted within the casing, a rod attached to the lever and a flexible bag, consisting of a body provided with two oppositely disposed bearing faces and an inlet neck or nozzle secured intermediate said bearing faces, said bag being adapted to shift the lever.
2. A switch operating device comprising a casing, a lever pivoted within the casing, a rod attached to the lever together with flexible bags adapted to alternately shift the lever in opposite directions; said bags consisting of bodies each provided with two oppositely disposed bearing faces and inlet necks or nozzles secured intermediate said bearing faces.
3. A switch operating device comprising a casing provided with a removable cover, a stuffing box located in one of its sides adjacent to the end, a lever pivoted inside the casing at its opposite end, a rod passing through the stuffing box and connecting with the free end of the lever, bags interposed between the lever and sides of the casing and adapted to alternately shift the position of the lever when inflated, together with means for inflating and deflating the bags alternately, substantially as described.
4. A switch mechanism actuator, consisting of a body provided with two oppositely

disposed bearing faces and an inlet neck or nozzle secured intermediate said bearing faces.

5. A switch mechanism actuator, consisting of a body provided with two oppositely disposed bearing faces, said faces being free from openings and an inlet neck or nozzle secured intermediate said bearing faces, substantially as described.

6. A switch mechanism actuator, consisting of a wedge shaped flexible body provided with oppositely disposed bearing faces and an inlet neck or nozzle secured to the smaller end thereof intermediate said bearing faces substantially as described.

7. A switch operating device comprising a closed casing, a lever pivoted within the casing, a rod attached to the lever, a stuffing box for said rod together with flexible bags adapted to alternately shift the lever in opposite directions, said bags consisting of wedge shaped bodies each provided with oppositely disposed bearing faces and inlet necks or nozzles secured to the smaller ends thereof between the bearing faces.

In testimony whereof I have hereunder signed my name in the presence of the two subscribed witnesses.

JOHN J. GARD.
